UNITED STATES PATENT OFFICE.

JOHN H. A. BOUSFIELD, OF ST. JOHNSBURY, VERMONT, ASSIGNOR TO E. AND T. FAIRBANKS AND COMPANY, OF ST. JOHNSBURY, VERMONT, A CORPORATION OF VERMONT.

LINK CONNECTION FOR TRACK-SCALE LEVERS.

1,184,921.

Specification of Letters Patent.

Patented May 30, 1916.

Application filed August 23, 1915. Serial No. 46,958.

To all whom it may concern:

Be it known that I, JOHN H. A. BOUSFIELD, a citizen of the United States of America, residing at St. Johnsbury, in the county of Caledonia and State of Vermont, have invented certain new and useful Improvements in Link Connection for Track-Scale Levers, of which the following is a specification, reference being had therein to the accompanying drawings.

The invention relates to railway track scales, and more particularly to the means for connecting the levers of the system with each other.

It is the object of the invention to obtain a simple construction which can be machined accurately to gage and length, and which permits of readily assembling the structure.

In the drawings: Figure 1 is a sectional elevation showing two levers of a track scale with my improved construction of link therebetween; Fig. 2 is an elevation at right angles to Fig. 1; and Figs. 3 and 4 are side and end elevations of a modified construction.

A is the main and B the extension levers of a railway track scale, which levers are arranged in transverse planes and are respectively provided with the knife edge bearings C and D also in transverse planes. To form a simple and easily assembled construction of linkage between these levers which will also provide perfect freedom of movement, I have devised the following construction. E is a loop, comprising substantially parallel bars, which at their ends are provided with eyes F for engaging a transversely-extending pin. The connecting portion G of the loop at the bend is provided with an aperture for receiving a transverse pin, and above this portion the side bars of the loop are bifurcated, as indicated at H. Between the eyes F there is arranged a bearing block I, which is mounted upon the transverse pivot pin J, and the ends of this pin are preferably threaded to receive securing nuts K outside of the member E. There is also a bearing block L which is rockably mounted on a pivot pin M passing through the aperture in the portion G, said bearing being preferably bifurcated to embrace the portion G. The pin M is secured

by nuts M' engaging threaded end portions of said pin, as shown in Fig. 2. The bearing block I engages a knife edge pivot C of the extension lever B and the bearing block L engages a knife edge pivot D of the main lever. The bifurcated sides H provide an opening in alignment with the pivot D, which facilitates the engagement of the parts.

With the construction as described, it is evident that the member E may be accurately gaged as to length between the apertures for the transverse pins J and M. Also that the bearing blocks I and L are accurately located by said pins. Thus the distance between said bearings is accurately determined. Furthermore, the bearings are arranged to rock upon their respective pins in transverse planes. Thus perfect freedom of movement is provided both for the swinging of the levers in relation to each other, and for permitting the bearing blocks to maintain full contact with the knife edge bearings.

In Figs. 3 and 4 I have shown a modified construction, in which a loop E' similar in construction to the loop E and provided with a similarly attached bearing part is connected with a coöperating link N. The adjoining ends of said links are provided with eyes which register with each other and a transverse pin O forms the coupling therebetween. The opposite end of the link N has an eye P which is in a transverse plane to that connected to the pin O, and which engages a supporting loop Q. The link N may be variously twisted so that the eyes at opposite ends thereof are in planes at any predetermined angular relation, which facilitates attachment to various systems of levers.

What I claim as my invention is:—

1. A link connection for scale levers, comprising a loop bar having registering eyes at the ends of the loop for receiving a transverse pin, a rockable member upon said transverse pin, and an eye formed in the connecting portion of the loop having an axis transverse to that of the registering eyes.
2. A link connection for scale levers, comprising a loop bar having registering eyes in its ends and an eye in the connecting portion of the loop having its axis transverse to

that of the registering eyes, pins engaging said eyes, and rockable members pivoted on said pins respectively embraced by said loop and embracing the connecting portion 5 thereof.

3. A link connection for scale levers, comprising a loop bar having registering eyes at the ends thereof and an eye formed in the connecting portion of said loop having 10 its axis transverse to that of said registering eyes, and a coöperating bar having eyes at opposite ends thereof in planes in predetermined angular relation to each other, one of said eyes being embraced by said loop, 15 and a pin for connecting said registering eyes and the coöperating bars.

4. A link connection for scale levers, comprising a bar having eyes at opposite ends thereof with their axes in transverse 20 planes, said eyes being adapted to receive machined cylindrical pivot pins, pivot pins

extending through said eyes, and bearings rockably mounted on said pivot pins.

5. A link connection for scale levers, comprising a bar having eyes at opposite ends thereof with their axes in transverse planes, one of said eyes being adapted to receive an accurately fitted pin, and a member rockably mounted upon said pivot pin. 25

6. A link connection for scale levers, comprising a bar having eyes at opposite ends thereof with their axes in transverse planes, said eyes being adapted to receive accurately fitted cylindrical pivot pins, and members mounted on said pins. 30

35 In testimony whereof I affix my signature in presence of two witnesses.

JOHN H. A. BOUSFIELD.
